TRANSLUCENT PANEL

Donald S. Barrows, Rochester, N. Y.

Application November 7, 1930, Serial No. 494,171

8 Claims. (Cl. 41—21)

The invention relates to a panel particularly designed and adapted for use in connection with electric or other lights and has for its general object the provision of a novel translucent panel by means of which a very artistic, ornamental and pleasing effect may be obtained and the light diffused instead of being concentrated at a point opposite the source.

An important object of the invention is to provide a composite panel including a base of clear or colored transparent or translucent material together with a superposed layer of translucent material of laminated character, the different laminae of which will operate to refract or otherwise divert light rays passing through it for obtaining a diffused effect.

Another object of the invention is to provide a panel having an artificial transparent or translucent base and a superposed translucent layer of natural material, the two substances having their characteristics combined to effect a diffusion of the light and to produce an artistic and ornamental light effect which will be not only pleasing but also restful to the eye of the observer.

A further object of the invention is to provide a light transmitting panel which may include a colorless or colored glass plate or pane and a superposed layer or sheet of mica preferably of the more or less mottled and translucent variety which is frequently unsuitable for the usual commercial uses on account of its lack of clearness and uniformity.

A still further object is to provide a light transmitting and diffusing panel of this character in which the elements may be held in their proper relation by any suitable means.

An additional object is to provide a panel of this character which will be simple and inexpensive to make, easy to assemble, efficient in use, attractive in appearance, and a general improvement in the art.

To the attainment of the foregoing and other objects and advantages, the invention preferably consists in the details of construction and the arrangement and combination of parts to be hereinafter more fully described and claimed, and illustrated in the accompanying drawing in which:

Figure 1 is an elevation of a panel constructed in accordance with my invention, parts being broken away, and

Figure 2 is a cross sectional view on a larger scale.

Referring more particularly to the drawing I have shown my panel as comprising a pane or sheet of glass 10, a superposed layer of translucent

material 11 and retaining means 12. The glass pane 10 may be fully transparent or of a type which is only translucent, depending upon the preference of the manufacturer and the intended use, and it may be either clear and colorless or of any desired color whatsoever depending upon the effect desired. The superposed layer 11 is preferably a sheet of mica of any appropriate thickness and to obtain the most attractive results it is advantageously of a cloudy, smoky or mottled type, such for instance as the variety commonly known as "pearl mica". The mica sheet lies flat against the glass base and may conceivably be secured thereto by a suitable adhesive, possibly Canadian balsam, or the superposed elements may be retained in their proper relation and prevented from relative shifting by means of the binder or frame indicated at 12, this frame being represented as channel shaped in cross section so as to overlie both sheets of material at the edges thereof. Details as to this feature and the shape and dimensions of the panel are obviously immaterial as there may be so many variations and modifications in these respects.

Assuming that the panel has been constructed in this manner it is to be understood that it is very appropriate for use in lighting fixtures or in fact wherever it is desired to modify and diffuse the light emanating from any ordinary source and at the same time to obtain an attractive effect. Regardless of the exact character of the base pane 10 I have found that light transmitted therethrough and passing through the mica sheet is thoroughly diffused so that the entire panel possesses a luminous effect throughout instead of the light being concentrated at a limited area on the panel between the light source and the eye of the observer. The reason for this is probably that the mica consisting naturally of a multiplicity of laminae refracts the light rays on a wide variety of angles. In addition to this diffusion effect any veins, spots, mottling or color variations in the mica will become visible and if such are present they will break up the uniformity of the luminous appearance of the panel and consequently avoid a monotonous effect.

From the foregoing description and a study of the drawing it will be apparent that I have thus provided a simple and inexpensive panel which is very suitable for use in lighting fixtures or the like on account of its mechanical and ornamental characteristics. It is thought that the construction and advantages should be readily apparent to one skilled in the art without further explanation.

While I have shown and described the preferred embodiment of the invention and have mentioned certain alternatives it should be understood that the right is reserved to make all such changes in the details as will not depart from the spirit of the invention or the scope of the claims hereunto appended.

Having thus described the invention, I claim:

- 10 1. A panel of the character described comprising a rigid light transmitting base formed of a pane of glass, and a sheet of mica substantially coextensive therewith superposed thereon.
- 15 2. A panel of the character described comprising a rigid light transmitting base formed of a pane of glass, and a sheet of mica substantially coextensive therewith superposed thereon and consisting of a plurality of laminae.
- 20 3. A panel of the character described comprising a rigid light transmitting base formed of a pane of glass, and a sheet of mica substantially coextensive therewith superposed thereon consisting of a plurality of laminae and of a translucent character.
- 25 4. A translucent panel comprising a rigid light transmitting base formed of a pane of transparent

glass, and a coextensive superposed layer of translucent mica.

5. A translucent panel comprising a rigid light transmitting base formed of a sheet of colored transparent glass, and a superposed substantially coextensive layer of translucent mica. 80

6. A translucent panel comprising a rigid light transmitting base formed of a sheet of colored transparent glass, and a superposed substantially coextensive layer of translucent mica of a contrasting color. 85

7. A translucent panel comprising a rigid light transmitting base formed of a sheet of colored transparent glass, and a superposed substantially coextensive layer of translucent mica of the pearl type. 90

8. A decorative light transmitting panel comprising a sheet of glass of a selected color, a continuous unbroken layer of mica substantially coextensive therewith and lying thereagainst, and a binder surrounding the edges of the glass and the mica and overlying both thereof for effecting securing together. 95

DONALD S. BARROWS.

100

- 30 1. A panel of the character described comprising a rigid light transmitting base formed of a pane of glass, and a sheet of mica substantially coextensive therewith superposed thereon.
- 35 2. A panel of the character described comprising a rigid light transmitting base formed of a pane of glass, and a sheet of mica substantially coextensive therewith superposed thereon and consisting of a plurality of laminae.
- 40 3. A panel of the character described comprising a rigid light transmitting base formed of a pane of glass, and a sheet of mica substantially coextensive therewith superposed thereon consisting of a plurality of laminae and of a translucent character.
- 45 4. A translucent panel comprising a rigid light transmitting base formed of a pane of transparent
- 50 5. A translucent panel comprising a rigid light transmitting base formed of a sheet of colored transparent glass, and a superposed substantially coextensive layer of translucent mica.
- 55 6. A translucent panel comprising a rigid light transmitting base formed of a sheet of colored transparent glass, and a superposed substantially coextensive layer of translucent mica of a contrasting color.
- 60 7. A translucent panel comprising a rigid light transmitting base formed of a sheet of colored transparent glass, and a superposed substantially coextensive layer of translucent mica of the pearl type.
- 65 8. A decorative light transmitting panel comprising a sheet of glass of a selected color, a continuous unbroken layer of mica substantially coextensive therewith and lying thereagainst, and a binder surrounding the edges of the glass and the mica and overlying both thereof for effecting securing together.
- 70 9. A translucent panel comprising a rigid light transmitting base formed of a sheet of colored transparent glass, and a superposed substantially coextensive layer of translucent mica of the pearl type.
- 75 10. A translucent panel comprising a rigid light transmitting base formed of a sheet of colored transparent glass, and a superposed substantially coextensive layer of translucent mica.
